UNITED STATES PATENT OFFICE

MICHAEL A. WILKINSON, OF OWEGO, NEW YORK

FOLDING TABLE

Application filed December 3, 1930. Serial No. 499,676.

My invention relates generally to tables and particularly to the folding or collapsible type of table used for banquets, card parties, etc.

5 The primary object of my invention is to provide a folding table which in folded position economizes to a considerable extent the amount of space required for stacking and storing same and which when set up for use affords a rigid substantial structure void of extraneous and unsightly contrivances, and thus simulates to a marked degree in design and appearance the ordinary nonfolding table.

15 Another and important object of my invention lies in the provision of a simple, compact operating mechanism whereby the user by operating one leg, simultaneously and automatically moves the other legs to either folded or upright position thus facilitating and expediting the operation and at the same time enabling one person to fold or unfold the table with a minimum of effort.

20 A further object of my invention contemplates the provision of a novel locking means which automatically locks and rigidly maintains the legs in upright position but which may be quickly and easily released for folding same to collapsed position.

25 Other objects and advantages in details of construction and operation will be apparent as the description proceeds, reference now being had to the figures of the accompanying drawings forming a part of this application and wherein like reference numerals indicate like parts.

In the drawings:

30 Figure 1 is a side elevational view of the table in unfolded or upright position.

Figure 2 is a bottom plan view thereof with a dotted line indication of the folded or collapsed position.

Figure 3 is a side view of the operating and locking mechanism.

Figure 4 is a top plan view of same.

Figure 5 is a cross sectional view taken on the line 5—5 of Figure 4.

Figure 6 is a cross sectional view taken on the line 6—6 of Figure 4.

Figure 7 is a cross sectional view taken on the line 7—7 of Figure 5.

The reference character 1 refers to the top to which, on the underside thereof, are secured two sets of legs 2 and 3 as by means of the cross members 4 and 5 respectively, joining the upper ends thereof, and the hinges 6. It will be noted with particular reference to Figure 2 that the set of legs 2 are mounted slightly off center to the right of the top 1 and that the set of legs 3 are mounted slightly off center to the left of same whereby when the legs are swung inwardly to collapsed or folded position as herein shown in dotted lines, they will cooperatively pass one another and nest together in parallel position on the under side of the top 1. The aforementioned parts are preferably made of wood. It should be understood, however, that they may be made equally as well of any sufficiently durable, light and substantial material which lends itself to this construction.

Mounted on the under side and centrally of the top 1 is a relatively long flange U-shaped housing 7 stamped or otherwise suitably formed of channel stock or other suitable material and secured thereto by screws 8 or other suitable fastening means. Elongated cigar shaped slots or openings 9 and 10 are struck or otherwise suitably formed longitudinally in the side of the U-shaped housing to permit the passage therein of V-shaped braces 11 and 12 which pass therethrough and extend angularly outwardly and downwardly in opposite directions and are pivotally secured at their lower ends as at 13 to the inner sides of the legs 2 and 3. The excess metal struck from the sides of the housing to form the slots 9 and 10 is bent inwardly to form flanges 9a and 10a along the edges of the slots for a purpose to be described. At what would normally be considered the apex of these V-shaped braces 11 and 12, in other words, at the point where they pass through the slots 9 and 10, they are bent or otherwise suitably formed horizontally as 13 and 14 for a sufficient distance beyond the sides of the housing 7 to permit free and unrestricted longitudinal movement.

in the slots 9 and 10 thereof. As before stated the slots 9 and 10 are cigar shaped viz., they are bellied at their centers as at 15 and arcuately tapered toward their opposite ends 16 and 17 to a width approximating the diameter of the braces 11 and 12, for a purpose to be described.

Slightly beyond the ends 16 and 17 of and on center with the slots 9 and 10 are cross shafts 18 and 19 rigidly secured between the sides of the U-shaped housing 7 as at 20 over and around which is adapted to pass an endless chain 21. Spaced flanges 22 are provided intermediate the ends of the cross shafts 18 and 19 to guide the chain 21 as it passes thereover. Interposed and secured as at 23 between two links on the upper side and two links on the lower side of this chain 21 and in cooperative spaced relation with each other are plates 24 and 25. These plates 24 and 25 extend horizontally across the housing 7 and terminate slightly within the sides of same, the upper plate 24 engaging at its extreme opposite ends the upper sides 25 of the upper set of flanges 9a and 10a of the slots 9 and 10 and the lower plate 25 engaging at its extreme opposite ends on the lower sides of the lower set of flanges 9a and 10a thereof. The horizontally disposed portions 26 of the upper set of flanges 9a and 10a of the slots 9 and 10 and the lower plate 25 engaging at its extreme opposite ends on the lower sides of the lower set of flanges 9a and 10a thereof. The horizontally disposed portions 27 and 28 of the V-shaped braces 11 and 12 are pivotally secured to these plates 24 and 25 respectively as by means of the straps or bands 26 which are riveted or otherwise suitably attached, thus holding the portions 29 and 30 of the braces 11 and 12 against the flanges 9a and 10a of the slots 9 and 10. At the point where the straps engage the horizontal portions 27 and 28 of the braces 11 and 12 said portions are slightly reduced in diameter thus forming a shoulder 31 as clearly shown in Figure 7 and thus insuring against sideplay. Obviously by virtue of the connections of the braces 11 and 12 with the chain 21 and legs 2 and 3 movement of one set of legs outwardly or inwardly simultaneously imparts similar movement to the opposite set of legs and vice versa.

Immediately beneath the lower side of the plate 25 is locking member 28 formed preferably of sheet stock, and pivotally secured at its ends by bending same as at 29 to form the pintles 30 adapted to be socketed in the upwardly bent portions 31 disposed at the opposite ends of the housing 7 adjacent one side thereof.

This locking member 28 is blanked, stamped or otherwise suitably formed adjacent its ends with outwardly extending fingers 32 as clearly shown in Figures 4, 5, and 6, the extreme ends of which are depressed as at 33 to form recesses for securing the ends of coil springs 34 thereto, the opposite ends of the springs 34 are anchored as at 35 in lugs or ears 36 struck from one side of the housing 7 or otherwise suitably provided

therein near the upper edge thereof whereby the locking member 28 is normally urged upwardly against the plate 25. Intermediate the ends of this locking member 28 is the outwardly extending portion 37 bent right angularly upwardly and formed at its upper edge on a parallel arcuate contour to the lower set of flanges 9a and 10a as at 38. This outwardly extending portion 37 and 38 terminates at each of its ends at a distance within the ends 16 and 17 of the slots 9 and 10 approximately that of the diameter of the braces 11 and 12 as at 39. The plates 24 and 25 are notched inwardly as at 40 flush with the horizontal portions 13 and 14 of the braces 11 and 12 at a point in alignment with the upwardly bent portion 38 of the locking member 28 to permit the passage therethrough of the upwardly bent portion 38 thereof. Centrally on the underside of the locking member 28 is rigidly secured a finger piece 41 extending downwardly therefrom through an opening 42 in the bottom of the housing 7 whereby the locking member 28 may be moved downwardly on its axis out of locking engagement with the braces 11 and 12. In such position it is obvious that as the legs 2 and 3 are folded inwardly the braces 11 and 12 will be slid inwardly toward one another and the portions 13 and 14 thereof will simultaneously be moved upwardly and downwardly from one another as they approach the centers of the slots 9 and 10 by virtue of the plates 24 and 25 attached thereto riding over the arcuate flanges 9a and 10a thereof thereby permitting the braces 11 and 12 to pass each other. In this position the locking plate 28 will be held downwardly against the tension of the springs 34 by the plate 25 engaging against the arcuately formed edge 38 thereof, said engagement being sufficiently frictional to hold the legs 2 and 3 in collapsed position. It will be clear that as the user moves either of these sets of legs 2 and 3 to upright position the opposite set of legs will be simultaneously moved to same position and the braces 11 and 12 attached therewith will be slid outwardly past one another until the portions 13 and 14 thereof abut against the ends 16 and 17 of the slots 9 and 10 whereupon the locking member 28 will snap upwardly into locking position and thus rigidly and securely maintain the legs 2 and 3 in said position.

I claim:—

1. In combination with a table having hinged legs and a top, a housing member on the underside of the table top, a pair of brace rods extending through said housing and slidably therein, the ends of said rods being pivotally secured to said legs, a movable endless member in said housing to which said rods are attached, whereby movement of one of said legs results in movement of all of said legs.

2. In combination with a table having hinged legs and a top, a housing member on the underside of the table top, a pair of brace rods extending through said housing and 5 slidable therein, the ends of said rods being pivotally secured to said legs, a movable endless member in said housing to which said rods are attached, whereby movement of one of said legs results in movement of all of said 10 legs, the sides of said housing being slotted to permit guided sliding movement of said rods.

3. In combination with a table having hinged legs and a top, a housing member on 15 the underside of the table top, a pair of brace rods extending through said housing and slidable therein, the ends of said rods being pivotally secured to said legs, a movable endless member in said housing to which said 20 rods are attached, whereby movement of one of said legs results in movement of all of said legs, the sides of said housing being slotted to permit guided sliding movement of said rods, said slotted sides being flanged 25 to form guides for said rods.

4. In combination with a table having hinged legs and a top, a housing member on the underside of the table top, a pair of brace rods extending through said housing and 30 slidable therein, the ends of said rods being pivotally secured to said legs, a movable endless member in said housing to which said rods are attached, whereby movement of one of said legs results in movement of all of said 35 legs, the sides of said housing being slotted to permit guided sliding movement of said rods, said slotted sides being flanged to form guides for said rods, and said slots being enlarged at their center portions to permit 40 free movement of said rods past each other in said housing.

5. In combination with a table having hinged legs and a top, a housing member on the underside of the table top, a pair of brace 45 rods extending through said housing and slidable therein, the ends of said rods being pivotally secured to said legs, a movable endless member in said housing to which said rods are attached, whereby movement of one 50 of said legs results in movement of all of said legs, the sides of said housing being slotted to permit guided sliding movement of said rods, said slotted sides being flanged to form guides for said rods, and said slots being 55 enlarged at their center portions to permit free movement of said rods past each other in said housing, and a locking lever normally urged to locking position and adapted to move between said rods when they have reached the 60 ends of the housing and opened the legs.

6. In combination with a table having hinged legs and a top, guiding means on the underside of said top, and a movable endless member guided by said guiding means, leg 65 braces attached at two opposite points on

said endless member, the braces from one point being connected to one pair of legs, and the braces from the other point being connected to the other pair of legs.

In testimony whereof, I affix my signature. 70
MICHAEL A. WILKINSON.
